Fig. 3.

Fig. 4.

Fig. 5.

FIGURE 1 is a perspective view of a chain drive juvenile vehicle showing my new design;

FIGURE 2 is a side elevation thereof;

FIGURE 3 is a top plan view thereof;

FIGURE 4 is a rear elevation view thereof; and

FIGURE 5 is a front elevation thereof.

The characteristic feature of this design comprises the forwardly convergent hood portion, provided with side exhaust pipes, in combination with the structural frame, all as shown.

I claim:

The ornamental design for a chain drive juvenile vehicle, substantially as shown and described.
